UNITED STATES PATENT OFFICE.

JOHN A. BOHNSACK, OF CLEVELAND HEIGHTS, OHIO, ASSIGNOR TO THE E. F. HAUSER-MAN COMPANY, OF CLEVELAND, OHIO, A CORPORATION OF OHIO.

JOINT BETWEEN METALLIC BUILDING ELEMENTS.

Application filed August 17, 1927. Serial No. 213,526.

The present improvement relates to joints between metallic building elements, and more particularly to construction adaptable for doors and framing units where glazing or 5 other panel filling elements may be employed.

It is among the objects of this invention to provide a construction which is simple and convenient for manufacture, strong and durable, consisting of few parts and pleasing 10 in appearance, especially by the avoidance of exposed welded joints. Also the proposed construction is sanitary and otherwise desirable by the elimination of exposed crevices between a multiplicity of parts. Other 15 objects and advantages will appear as the description proceeds.

This invention consists of the features hereinafter described, and particularly pointed out in the claims; the following description 20 and the annexed drawing setting forth but one illustrative embodiment of the various forms in which the principle of the invention may be applied.

In said annexed drawing—

25 Fig. 1 is a broken interior perspective view showing part of the bottom of a door constructed in accordance with this invention; and Fig. 2 shows a fragmentary broken sectional detail.

30 Of the door thus chosen for the purpose of illustration, the parts or elements appearing in the foregoing figures include the stile 1, the bottom rail 2, and a reinforcing member 3. The joint between the side stile 1 and end or 35 bottom rail 2 is featured by having the end of the bottom rail 2 bent in to form a reinforcing flange 4, and the stile 1 has a corresponding offset or complementary flange 5 forming thereby a line joint 6, which it is 40 desired should extend to the end of the stile. Such construction it will be seen, causes a projection formed of such complementary flanges to extend within the joint to the margin of the door and it is the especial purpose 45 of this invention to provide a suitable and convenient means of reinforcing a joint under such circumstances.

The reinforcing member 3 preferably consists as shown of a piece of sheet metal bent 50 into a channel section, with the opening of the channel directed down-wardly, although

its position may be the reverse of that shown, if desired.

In order to permit such channel reinforcing member 3 to enter the stile and bottom 55 rail where they adjoin, a portion of the flange 5 is cut away to leave a notch 7; while to allow said reinforcing member to clear the remainder of the interfering metal, notches 8 are cut out of the web thereof, and the parts 60 11 of the flanges or vertical portions 9 of said member, which are adjacent to the notches 8 are embossed or pressed inwardly a sufficient amount to allow reinforcing member 3 to rest upon the inner surface of stile 65 1 and bottom rail 2 without touching projection 10.

When thus formed, reinforcing member 3 is strong and durable and suitable for welding or otherwise fastening the flanges 9 to the 70 stile 1 and bottom rail 2.

Other modes of applying the principle of this invention may be employed instead of that explained, change being made as regards the features herein disclosed, provided 75 the means stated by any of the following claims or the equivalent of such stated means be employed.

I therefore particularly point out and distinctly claim as my invention:

1. A channel reinforcing member for a joint between hollow metallic building elements, the web of said channel having notches therein, and, adjacent to said notches, the flanges of said channel having sections thereof embossed or pressed inwardly to provide clearance for interfering projections on said elements.

2. In a joint for hollow metallic building elements the combination with inwardly directed, complementary flanges on the meeting edges of said elements, of a channel type reinforcing member, fitting into said elements, the web of said channel having notches therein and adjacent to said notches the 95 flanges of said channel having sections thereof embossed or pressed inwardly to provide clearance for the flanges on said elements, a portion of said last named flanges being removed to provide clearance for said channel 100 member.

3. In a joint for hollow metallic building

elements, the combination with an element channel being embossed or pressed inwardly having an inwardly directed reenforcing adjacent such notches to provide clearance flange and another element having an offset for the flanges on the aforesaid elements. 10
to receive said flange and form a line joint, Signed by me this 13th day of August,
5 and a channel type reenforcing member fitting into said elements, the web of said channel having notches and the flanges of said

JOHN A. BOHNSACK.
